UNITED STATES PATENT OFFICE.

REGINALD L. GOODING, OF BARBADOS ISLAND, BRITISH WEST INDIES.

DESIGN FOR A BACK FOR PLAYING-CARDS OR SIMILAR ARTICLES.

51,724.

Specification for Design.

Patented Feb. 5, 1918.

Application filed October 10, 1917. Serial No. 195,863. Term of patent 7 years.

To all whom it may concern:

Be it known that I, REGINALD L. GOODING, a subject of the King of England, residing at Barbados Island, in the British West Indies, have invented a new, original, and ornamental Design for the Backs of Playing-Cards or Similar Articles, of which the following is a specification, reference being had to the accompanying drawing, forming part thereof.

The figure is an elevation of the back of a playing card, showing my new design.

I claim:

The ornamental design for a back for playing cards or a similar article as shown.

REGINALD L. GOODING.
